CHAISE LOUNGE

Arthur W. Eilsworth, South San Gabriel, and Robert K. Fujioka, Los Angeles, Calif., assignors to Samsonite Corporation, Denver, Colo., a corporation of Colorado

Filed June 7, 1965, Ser. No. 85,609

Term of patent 14 years

(Cl. D15—1)

FIG. 1.

FIG. 2.

FIG. 3.

FIG. 1 is a perspective view, showing the front and one side, of a chaise lounge embodying our new design;

FIG. 2 is a side elevation showing the opposite side of the chaise lounge of FIG. 1; and

FIG. 3 is a rear elevation of the chaise lounge of FIG. 1.

We claim:

The ornamental design for a chaise lounge, as shown.
